UNITED STATES PATENT OFFICE.

DORSEY E. McLAUGHLIN, OF TACOMA, WASHINGTON.

SEAL-LOCK.

SPECIFICATION forming part of Letters Patent No. 739,701, dated September 22, 1903.

Application filed August 28, 1902. Serial No. 121,389. (No model.)

To all whom it may concern:

Be it known that I, DORSEY E. McLAUGHLIN, a citizen of the United States, residing at the Irving Hotel, Tacoma, in the county of Pierce and State of Washington, have invented certain new and useful Improvements in Locks or Sealing Devices for Freight-Box-Car Doors; and I do hereby declare the following to be a full, clear, and exact description of the invention, such as will enable others skilled in the art to which it appertains to make and use the same.

This invention relates to improvements in door-locks, and is especially designed for sealing doors, particularly those in use upon cars, such as freight-cars, baggage-cars, express-cars, and the like.

It consists in a lock having a locking member and a sealing member, the locking member dropping into its locked position opposite the door or into its unlocked position and the sealing member accommodating itself to the positions assumed by the locking member.

It also consists in certain other novel constructions, combinations, and arrangements of parts, as will be hereinafter fully described and claimed.

In the accompanying drawings, Figure 1 is a side elevation of a portion of a car and a car-door, showing the lock in its locked position. Fig. 2 is a transverse sectional view through the side of a car and through the casing inclosing the lock, the parts being shown in their locked position. Fig. 3 is a similar view with the parts shown in their unlocked position. Fig. 4 is a horizontal sectional view through the lock.

The lock forming the subject-matter of the present invention, while applicable to sliding doors of various kinds, is particularly adapted for use in connection with sliding doors of railway-cars. The lock mechanism is preferably inclosed in a suitable casing 1, which is let into the side of a car, so as to be flush with the same at its forward edge, the said casing extending inwardly and occupying a space between the outer siding 2 and the inner lining 3 thereof. Within the casing 1 is pivoted a locking member 4 and a sealing and weather-excluding member 5.

The locking member 4 is angular in shape and is pivoted, as at 6, near its lower edge. The arms of the locking member extend approximately at right angles to each other from the said pivot. When the lock 4 is in its unlocked position, it is resting upon its lower edge and is entirely within the casing 1, as clearly shown in Fig. 3 of the drawings. When the lock is in its locked position, as shown in Fig. 2, one of its arms extends at right angles from the casing 1 and into the path of the door 7. When the door is closed and the locking member is turned down behind it, the door cannot be slid to its open position. The locking-arm of the locking member is formed with a downwardly-projecting lug 8, which engages a correspondingly-formed recess 9 in a keeper-plate 14, which is secured to the rear edge of the door 7. The keeper-plate is also formed with a vertical flange 11, by which it is secured to the door, which coincides with a portion of the locking-arm of the locking member 4, and coinciding recesses 12 and 13 are formed in the said locking member and keeper-plate, respectively. When the arm of the locking member is turned downwardly, these apertures 12 and 13 will register with each other, and any suitable locking-bolt may be passed through them for positively holding the locking member in its locked position. The recess 9 is formed in a horizontal flange 14, projecting to one side of the vertical flange 11 of the keeper-plate. The inner arm 15 of the locking member is thickened to form a weight, the weighted portion being so disposed with respect to the pivot 6 that it will tend to hold the locking member either in its unlocked or locked position. The sealing and weather-excluding member 5 is pivoted in the upper part of the casing 1 and at the forward edge thereof upon a suitable pin, as at 16. This sealing member is formed with an elongated depending portion 17 and a short projecting nose or weather-excluding portion 18, extending at right angles to the portion 17. When the sealing member is forced inwardly in the casing 1 to a horizontal position, the nose 18 will extend downwardly from the upper end of said arm, serv-

ing to exclude weather from the casing and the parts, as shown in Fig. 3. When the parts are in their locked position, the projection 18 extends outwardly, as shown in Fig. 5 2, thus still protecting the parts of the locking mechanism. When the parts are in their locked position, a hooked portion 19 upon the locking member 4 projects through a slot 20, formed in the lower end of the sealing member, its outer end extending beneath a slotted projection 21 on the sealing member. This hooked projection 19 and the projection 21 are each formed with coinciding apertures, as at 22 and 23, respectively, which coincide 15 with each other when the parts are in their locked position, so that a seal of any suitable kind may be attached to these projections, and the lock cannot be brought to its unlocked position without breaking or mutilating such seal. When the parts are in this 20 locked position also, the lower end of the sealing member 5, which is somewhat thickened, as at 24, will rest in an offset or recessed portion 25, formed in the locking member 4, and further assist in holding the parts in their locked position. The locking member 4 can also be further secured by a seal by placing such seal through the coinciding apertures 12 and 13. In this manner the locking-arm of the locking member 4 cannot be 25 raised out of the path of the door without first breaking such seal.

In unlocking the door when the locking member 4 is raised the projection 19 will first 30 slide out of the aperture 20, after which the sealing member can be forced inwardly, when the arm of the member 4 engages the same. The weight 15 of the locking member is so disposed that when the parts approach their 35 unlocked position the weight will complete the movement and maintain the parts in this position until it is desired to lock the door again. When the door is to be locked, the locking member is drawn outwardly until 40 the weighted portion comes forward to the pivot 6, when it will tend to complete the motion and maintain the parts in their locked position. The outer edge of the locking-arm of the member 4 is formed with a down- 45 wardly and outwardly projecting hooked portion 26, which may be engaged by the fingers or any suitable implement for drawing the locking member out of its casing.

It will be observed from the above description 50 that the parts of the lock are comparatively simple in structure and yet are very effective for the purposes designed, and it is impossible to open the door when the locking member is out of its casing.

60 Having thus fully described my invention, what I claim as new, and desire to secure by Letters Patent, is—

1. A door-lock, comprising a locking member, and a coöperating sealing member, the 65 locking member being pivoted so that it may

be turned downwardly opposite the end of a sliding door, and a weighted portion forming a part of the locking member, so disposed as to be thrown to one side or the other of the pivotal point of said locking member for holding it either in its locked or its unlocked position, substantially as described. 70

2. A door-lock comprising a movable locking member formed with a locking-arm and a weighted arm having a recess, and a movable sealing member coöperating therewith, the locking-arm of the locking member being turned downwardly opposite the edge of the door to prevent its being opened, substantially as described. 75

80 3. A door-lock comprising a locking member and a sealing member, a housing for inclosing and pivotally supporting the same, a locking member having a locking-arm projecting therefrom and adapted to be turned down opposite the door to be locked, and a keeper-plate carried by the door, a projection on the locking member for engaging the keeper-plate, and means for locking the member to the said keeper-plate, substantially as 85 described. 90

4. A lock for doors comprising a pivoted locking member having a weighted arm and a locking-arm, the weight being so arranged with relation to the pivotal point of said locking member that it will hold the same either in its locked or unlocked position, and means for positively fastening either the weighted arm or the locking-arm of the locking member when in its locked position with a suitable seal, substantially as described. 95 100

5. A locking mechanism for sliding doors comprising a locking member and a sealing member, the locking member having a locking-arm and a weighted arm, a hooked projection carried by the weighted arm, a sealing member pivoted above the locking member and formed with a recess for receiving the hooked portion of the locking member, a projection on the sealing member extending parallel with the end of the projection on the locking member both of said projections being apertured for receiving a suitable seal which seal prevents the unlocking of the parts, substantially as described. 105 110 115

6. A locking mechanism for sliding doors comprising a pivoted locking member and a sealing member the sealing member having a projection extending therefrom for keeping weather away from the parts, and means 120 for connecting the locking member and the sealing member by means of a suitable seal, substantially as described.

7. A locking mechanism for sliding doors comprising a pivoted locking mechanism and a sealing mechanism, an inclosing casing for supporting the same, the said members entirely folding within the casing in their unlocked positions, a hooked projection on the locking member for drawing the same out. 125 130

wardly, a lug on the locking member for engaging a keeper-plate, and an apertured projection also on said locking member by which it may be locked to said keeper-plate, and 5 means for securing the locking member in its locked position by a suitable seal, substantially as described.

In testimony whereof I hereunto affix my signature in presence of two witnesses.

DORSEY E. MC LAUGHLIN.
